UNITED STATES PATENT OFFICE

1,976,827

RAILWAY SWITCH OPERATING APPARATUS

Herbert L. Bone, Swissvale, Pa., assignor to The Union Switch & Signal Company, Swissvale, Pa., a corporation of Pennsylvania

Application July 1, 1932, Serial No. 620,421

52 Claims. (Cl. 246—253)

My invention relates to railway switch operating apparatus.

One object of my invention is to provide a facing point lock for a spring switch so constructed that the locking plunger thereof will be automatically operated by means mechanically actuated by a train which is trailing the switch to unlock the switch, and will be automatically restored to its locking position to re-lock the switch after the movable rails have returned to their normal positions upon completion of the trailing movement.

Another object of my invention is to provide a circuit controller controlled by the locking plunger of the lock for indicating when the switch is properly locked for a facing point move, and when the locking plunger is in proper adjustment to cause it to be automatically withdrawn during a trailing move.

Other objects of my invention will become apparent as the description proceeds.

I will describe several forms of apparatus embodying my invention, and will then point out the novel features thereof in claims.

In the accompanying drawings, Fig. 1 is a top plan view showing a spring switch A controlled by a switch operating mechanism B constructed in accordance with my invention. Fig. 2 is an enlarged transverse sectional view of the spring connecting rod C forming part of the apparatus illustrated in Fig. 1. Fig. 3 is an enlarged top plan view of the switch operating mechanism B shown in Fig. 1, with the several covers removed to better illustrate the construction of the mechanism. Fig. 4 is a longitudinal sectional view of the mechanism shown in Fig. 3. Fig. 5 is a detail sectional view taken substantially on the line V—V of Fig. 3. Fig. 6 is a sectional view taken on the line VI—VI of Fig. 3. Fig. 7 is a diagrammatic view showing one arrangement of controlling circuits which may be used in connection with the apparatus illustrated in Fig. 1, which circuits also embody my invention. Fig. 8 is a diagrammatic view

showing another arrangement of controlling circuits which may be used in connection with the apparatus illustrated in Fig. 1, and also embodying my invention. Fig. 9 is a front elevational view of a signal adapted to be used in place of the circuit controller E shown in Figs. 3 and 4 and the signals S¹ and S² shown in Fig. 1. Fig. 10 is a vertical sectional view of the signal shown in Fig. 9. Figs. 11 and 12 are detail views showing modifications of a portion of the apparatus illustrated in Fig. 1.

Fig. 13 is a top plan view showing a modified form of a portion of the apparatus illustrated in Figs. 1, 3 and 4, and also embodying my invention. Fig. 14 is a longitudinal vertical sectional view of the mechanism B¹ shown in Fig. 13. Fig. 15 is a sectional view on the lines XV—XV of Fig. 14. Fig. 16 is a top plan view showing another modified form of a portion of the apparatus illustrated in Fig. 1, and also embodying my invention. Fig. 17 is a detail view showing in said elevation a portion of the apparatus illustrated in Fig. 16. Fig. 18 is a top plan view showing still another modified form of the apparatus illustrated in Fig. 1, and also embodying my invention. Fig. 19 is a sectional view of the spring connecting rod C¹ forming part of the apparatus illustrated in Fig. 18. Fig. 20 is a top plan view showing still another modified form of the apparatus illustrated in Figs. 1, 3 and 4 and also embodying my invention.

Similar reference characters refer to similar parts in each of the several views.

Referring first to Fig. 1, the reference character A designates a railway switch comprising, as usual, two fixed rails 1 and 1^a and two movable rails 2 and 2^a. The fixed rails 1 and 1^a are laid on tie plates 3 and are secured to crossties 4 in the usual manner. The movable rails 2 and 2^a are fastened together by a front rod 5, a head rod 6, a bridle rod 7, and a tie rod 8, and may be moved into a normal or a reverse position by means of a switch operating mechanism B which is connected with the head rod 6 through the medium of an operating rod 9 and a spring connecting rod C. When the switch occupies its normal position in which position it is shown in Fig. 1, the movable rail 2 engages the fixed rail 1, and the movable rail 2^a is spaced a slight distance from the fixed rail 1^a. When the switch is reversed, however, the switch rail 2^a then engages the fixed rail 1^a, and the movable rail 2 is spaced from the fixed rail 1.

The spring connecting rod C may have any suitable form, but in the well known form here illustrated, this connecting rod comprises a cylindrical housing 10 having a lateral extension 10^b fastened to the head rod 6 (see Fig. 2). The lower end 10^b of the housing 10 has a smaller diameter than the body of the housing, while the upper end is threaded to receive a cap 11 having an end 11^a similar to the end at 10^b. Slidably mounted in the opening in the end 10^b is a sleeve 12 provided with an annular flange 110

12^a located within the housing 10, and similarly mounted in the opening in the end 11^a is a sleeve 13 provided with an annular flange 13^a which is also located within the housing 10. A 5 spring rod 14 extends through the sleeves 12 and 13 with sufficient clearness to permit the rod to slide freely in the sleeves and this rod carries a compression spring 15 which engages the sleeves at their annular flanges and urges the sleeves toward the positions in which the 10 annular flange 12^a of the sleeve 12 engages the shoulder formed on the inside of the housing 10 by the end 10^b, and the annular flange 13^a of the sleeve 13 engages the shoulder formed 15 on the inside of the cap 11 by the end 11^a. The spring rod 14 is provided with an annular shoulder 16 for at times engaging the outer end of the sleeve 12 and with a nut 17 for at times engaging the outer end of the sleeve 13. The 20 lower end of the spring rod 14 is pivotally attached to the operating rod 9. The operation of the spring connecting rod C is well understood and need not, therefore, be described here. The head rod 6 is also connected by means 25 of an adjustable link 49 with the piston rod 50 of a buffering device D. This buffering device may be of any suitable type but, as here shown, this buffering device is similar in all respects to the buffering device shown and described in an application for Letters Patent of the United States, Serial No. 391,801, filed by William C. McWhirter on September 11, 1929, for Buffering devices for railway switches and the like, which application has now matured into Patent No. 1,869,604, dated Aug. 2, 1932. It is believed, therefore, 30 that for the purposes of the present disclosure the following brief description of the buffering device D will suffice. This buffering device includes, in addition to the piston rod 50, a cam shaft 51 extending into the case of the device and controlling a valve mechanism not shown. Attached to the outer end of the cam shaft 51 is a crank 52 which is connected by a link 53 with the spring rod 14 of the spring connecting rod 40 C. If, when the movable rails 2 and 2^a of the switch A are in their normal positions, as shown in Fig. 1, they are moved to their reverse positions by the mechanism B, the piston rod 50 will be moved into the device, and the cam shaft 51 will be rotated in a clockwise direction, as viewed from the left in Fig. 1. The construction of the device is such that, under these 45 conditions, the piston rod 50 will be permitted to move with substantially no resistance, and the buffering device will therefore exert practically no retarding action on the rails. Conversely, if the movable rails are moved from their reverse positions to their normal positions by the mechanism B, the piston rod 50 will be moved outwardly and the cam shaft 51 will be rotated in a counter-clockwise direction, as viewed from the left in Fig. 1, but due to the construction of the device, no retarding action will again take place. If, however, when the movable rails are 55 in either extreme position, a train trails the switch, the cam shaft 51 will remain stationary, and, under these conditions, the action of the device is such that the movement of the movable rails away from the positions which they previously occupied will be unresisted by the buffering device, but that, when the movable rails are being restored to the positions which they previously occupied, by the spring 15 of the spring connecting rod C, the buffering device will act to retard this latter movement.

The switch operating mechanism B is mounted on one end of a tie strap 18 which is secured to the ties adjacent the outer side of the rail 1, and, as best seen in Figs. 3 to 6, inclusive, 80 this mechanism, in the form here shown, comprises a main casing 19 provided with a tail-like projection 19^a, and an auxiliary casing 20 which is secured to the tail-like projection 19^a of the main casing 19. The upper end of the main casing 19 is closed by a cover 21 and a guard 22, which cover and guard are removably secured to the casing by means of studs 23, while the auxiliary casing 20 is closed by a hinged cover 24.

Formed in the main casing 19 is an axially extending rectangular guideway 25 which slidably receives a motion plate 26. The motion plate 26 is provided on its upper face with rack teeth 27, and on its lower face with a cam slot 28, and is adapted to be reciprocated between 90 two extreme positions by means of a hand-throw lever 30 fixed to a shaft 31. The shaft 31 is journaled in suitable bearings 32 secured to the casing 19, and has fixed thereto a segment gear 33 which meshes with the rack teeth 27. 100 As best seen in Fig. 3, the cam slot 28 is formed with a portion at each end which is parallel to the direction of movement of the motion plate, and with an intermediate connecting portion which is disposed at an angle to the direction 105 of movement of the motion plate. Extending into the cam slot 28 and cooperating therewith is a roller 34 which is mounted on a pin 35 secured to an arm 36 forming part of a crank 37. The crank 37 is journaled in a vertical bearing 110 38 provided in the bottom of the casing 19 and has fixed thereto on the underside of the casing, a removable switch operating arm 37^a which is pivotally attached to the free end of the operating rod 9.

Reciprocably mounted in the casing 19 directly above the motion plate 26 is a locking device 39 comprising two spaced parallel side members 39^a and 39^b connected together at their opposite ends by means of integral end members 39^c and 39^d. The left-hand end member 39^c carries a rectangular locking plunger 39^e, and is formed with two spaced threaded holes 39^f and 39^g, while the other end member 39^d is provided with three unthreaded holes 39^h, 39ⁱ, and 39^k, two of 120 which holes, 39^h and 39^k align, respectively, with the threaded holes 39^f and 39^g. The locking plunger 39^e projects with some clearance into a longitudinally extending rectangular slot 44 provided in the tail-like projection 19^a of the casing 130 19, and cooperates at its inner end with a lock rod L which is slidably mounted in a transverse slot 45 formed in the tail-like projection 19^a. The lock rod L, in the form here shown, is of standard construction, and comprises two longitudinally adjustable bars 46 and 47 attached at one end to the front rod 5 of the switch A, and provided with registering notches 48 so disposed that these notches will align with the locking plunger 39^e when and only when the switch A 135 occupies the extreme position in which it is shown in Fig. 1. The locking device 39 also comprises two bolt members 39^l and 39^m which pass through the holes 39^h and 39^k, respectively, and are screwed into the threaded holes 39^f and 39^g. These bolt members also extend with some clearance through holes 40 and 41 formed in lugs 42 and 43 secured to the upper face of the motion plate 26, and surrounding each bolt member between the associated lug 42 or 43 and the 140 145 150

end member 39^a is a compressed coil spring 39^a which biases the locking device 39 in the direction to cause the locking plunger 39^a to enter the notches 48 in the lock rod L.

- 5 Vertical displacement of the locking device 39 and the motion plate 26 are prevented by a hold-down member 114 (see Fig. 6) which hold-down member is bolted to the side of the casing 19, and which is provided on its underside near its 80 ends with hold-down surfaces 114^a and 114^b which are adapted to slidably engage the upper edges of the side members 39^a and 39^b respectively, of the locking device 39.
- 10 For reasons which will become apparent as 85 the description proceeds, the parts of the locking device 39 are so proportioned that when the motion plate 26 is in its left-hand or normal extreme position as shown in Fig. 1, the biasing spring 39^a will tend to drive the locking device 90 to an extreme position which is beyond the desired locking position. The locking device is prevented from moving beyond the desired locking position, under these conditions however, by linkage which connects the locking device 95 25 with the tie rod 8. As here shown, this linkage includes a plunger bolt 54 which extends with some clearance through the hole 39^b in the end member 39^a, and the head of which bolt engages the left-hand side of the end member 39^a, 100 as viewed in Figs. 3 and 4. The threaded end 105 of the plunger bolt 54 is adjustably connected by means of a turn buckle 55 (see Fig. 1) with one end of a link 56, the opposite end of which link is pivotally connected with the long arm 57^a of a bell crank lever 57. The bell crank lever 57 is pivotally supported in a crank stand 58, and has its short arm 57^b pivotally connected with one end of an operating rod 59. The other 110 40 end of the operating rod 59 is connected with the previously described tie rod 8 by means of a standard switch basket 60. The tie rod 8 may be located at any suitable location, but will preferably be located approximately half-way between the heel and the point of the switch. The base 115 45 61 of the crank stand 58 is secured both to a gauge plate 62 and to the tie strap 18 upon which the mechanism B is mounted, and it will be apparent, therefore, that any loss of adjustment between the parts due to creepage of the 120 50 ties is prevented. The plunger bolt 54, turn buckle 55, link 56, bell crank lever 57, operating rod 59, spring basket 60, and tie rod 8, also constitute means for effecting the unlocking of 125 55 the switch points during a trailing move, as will be made clear presently.

- The operation, as a whole, of the portion of the apparatus thus far described is as follows: When the hand-throw lever 30 occupies the extreme position in which it is shown in full lines in Figs. 1 and 3, the motion plate 26 is held in its extreme left-hand or normal position as viewed in Figs. 3 and 4, and the roller 34 on the crank 37 then occupies the right-hand end of the cam slot 28, in the motion plate, so that the crank 37 is held at the extreme end of its stroke in a clockwise direction, as viewed in Figs. 1 and 3. When the crank 37 occupies this extreme position, a force is exerted on the movable rails 2 and 2^a of the switch through the medium of the operating rod 9, spring rod 14, nut 17, sleeve 13, spring 15, housing 10, and the head rod 6, which force holds the movable 140 70 rails in their normal extreme positions in which 145 75

they are shown in Fig. 1. When the movable rails are in their normal positions, the notches 48 in the lock rod L align with the locking plunger 39^a, and the locking device 39 is therefore moved by the biasing springs 39^a to its locking position in which the locking plunger partly enters the registering notches 48, thus securely locking the switch points in their normal positions.

When it is desired to reverse the switch, the hand-throw lever 30 is rotated from the extreme position in which it is shown in full lines in Fig. 1, to its opposite extreme or dotted line position. This movement of the lever causes the motion plate 26 to move from its extreme left-hand position, as viewed in Figs. 3 and 4, to its extreme right-hand position. As soon as the motion plate has moved a short distance, the lugs 42 and 43 carried thereby engage the left-hand side of the end member 39^a of the locking device 39, and as a result, as the motion plate continues to move, the locking device is moved with the motion plate, thus withdrawing the locking plunger from engagement with the notches 48 in the lock rod L, and hence unlocking the movable rails 2 and 2^a. The parts are so proportioned that while the locking plunger 39^a is being withdrawn from engagement with the notches 48 in the lock rod, the cam slot 28 in the motion plate will continue to engage the roller 34 on the crank 37 at that portion of the slot at its right-hand end which is parallel to the direction of movement of the motion plate, and as long as this portion of the slot is engaging the roller, the crank 37 will remain stationary. It follows, therefore, that during that portion of the movement of the motion plate which is necessary to unlock the movable rails of the switch, no force is exerted on these rails tending to reverse them. As soon, however, as this first part of the movement of the motion plate has been completed, the roller 34 is then engaged by the curved portion of the cam slot 28 which causes the crank 37 to be rotated in a counter-clockwise direction, as viewed in Fig. 3, and as a result, the rails are then moved to their reverse positions. As previously pointed out, when the rails are moved to their reverse positions by the mechanism B, the piston rod 50 of the buffering device D is moved into the device, and the cam shaft 51 is rotated in a clockwise direction, as viewed from the left in Fig. 1, but due to the construction of this device, the device offers substantially no resistance to the movement of the rails under these conditions. It should be noted that as long as the movable rails remain stationary, the plunger bolt 54 remains fixed, so that during the first part of the movement of the motion plate, the end member 39^a of the locking device 39 will move out of engagement with the head of the plunger bolt. As soon as the movable rails have started to move, however, the resultant movement of the tie rod 8 acting through the switch basket 60, operating rod 59, bell crank lever 57, and link 56 causes the plunger bolt to move in the same direction as the motion plate is moving, although the time of motion and rate of motion of the plunger bolt will bear no direct relation to the movement of the motion plate. During the final movement of the motion plate, the portion of the cam slot 28 in the motion plate at the left-hand end of the slot which is parallel to the direction of movement of the motion plate 150

engages the roller 34, which prevents further rotation of the crank 37, thus locking the movable rails in their reverse positions.

In order to restore the movable rails to their normal positions after they have been reversed as above described, the lever 30 is restored to the position in which it is shown in full lines in the drawings. The subsequent movements of the parts under these conditions are just the reverse of those described above, and it is believed, therefore, that the operation of the apparatus under these conditions will be readily understood from an inspection of the drawings without further description.

15 I will now assume that the parts are in their normal positions, as shown in the drawings, and that a train trails the switch. As the leading wheels of the train roll along the fixed rail 1 and the movable rail 2^a, the movable rails 2 and 20 2^a are forced over laterally, but, before a sufficient force is developed to overcome the opposing force of the spring 15 of the spring connecting rod C and cause the point of the movable rail 2 to move out of engagement with fixed rail 25 1, the movable rails being somewhat resilient become bent, so that, with the usual standard split switch, the tie rod 8 is moved upwardly, as viewed in Fig. 1, three-quarters of an inch or more. This movement of the tie rod acting 30 through the switch basket 60, operating rod 59, bell crank lever 57, link 56, and plunger bolt 54 moves the locking device 39 in opposition to the bias of the springs 39^a a sufficient amount to withdraw the locking plunger 39^e 35 completely out of engagement with the notches 48 in the lock rod L, thus unlocking the switch. As a result, when the leading wheels have reached the position in which a sufficient force is developed to cause the point of the movable 40 rail 2 to move out of engagement with the fixed rail 1, the switch points will be unlocked, and the points will therefore be forced open by the wheels in exactly the same manner as would be the case if no point lock were provided, and the buffering device D will perform its 45 usual function of preventing the movable rails from snapping back after the passage of each wheel through them. When the train which is trailing the switch has completely passed the switch, the movable rails will slowly return to 50 their normal positions under the bias of the spring 15 of the spring connecting rod C, and against the retarding force of the buffering device D. During this return movement of the 55 movable rails there will be no deflection of these rails, and the locking plunger 39^e will be moved into engagement with the lock rod L before the movable rails have reached their full normal positions in which the lock rod is in the proper 60 position for the notches 48 therein to receive the locking plunger. The spring 39^a will therefore become compressed, and will urge the locking plunger 39^e into engagement with the side of the lock rod, until the notches 48 move into 65 alignment with the locking plunger, at which time the energy stored in the compressed springs 39^a will force the locking plunger into place in the notches, thus restoring the switch to its normal locked condition. If the notches 48 in 70 the lock rod should not come into alignment with the locking plunger, a suitable indication of this fact will be given by means of a circuit controller E which I will describe presently.

75 During a facing point move, there is no lateral thrust on the movable rails corresponding

to, or commensurate with, that which occurs during a trailing movement and what lateral thrust there is will be in the direction to permit the springs 39^a to force the locking plunger further into the notches 48 in the lock rod L.

It will be noted that when the parts are in their normal positions as shown in Fig. 1, the reaction of the biasing springs 39^a is transmitted through the rack teeth 27 and segment gear 33 to the switch-throw lever 30, which tends to raise this lever. However, this lever is so designed that it has sufficient weight to resist and overcome this reaction. Furthermore, if it is undesirable for any reason to provide the lever 30 with sufficient weight to overcome the reaction of the springs 39^a, this lever may be held down by a conventional gravity lever latch stand, two of which stands are indicated at 91 in Fig. 1.

It will also be noted that when the parts are in their normal positions as shown in Fig. 1, since the springs 39^a tend to drive the locking device to an extreme position which is beyond its normal locking position, but are prevented from doing so by the linkage connecting the locking device with the tie rod 8, these springs will cause a force to be exerted on the movable rails at the point where the tie rod 8 is connected with the rails, and this force which, due to the mechanical advantage afforded by the bell crank lever 51 is relatively large, aids the force exerted by the spring 15 of the spring connecting rod in restoring the movable rails to their proper positions after the switch has been trailed, or after the switch has been operated to its normal position by the hand lever. In most switch layouts when the switch points are in their proper normal positions, the entire length of the movable rail 2 between the tip of the rail and the position where the tie rod 8 is connected with the rail, will be in contact with the stock rail 1, and in those switch layouts where this is not the case, fixed stops will usually be provided for the movable rail 2 at the point where the tie rod 8 is connected with this rail. It will be seen, therefore, that with apparatus embodying my invention, when the switch points are in their proper normal positions, the movable rail 2 at the point at which the tie rod 8 is attached to this rail will be constantly urged into engagement with a definite stop by a relatively large force, thus insuring that as long as the linkage connecting the tie rod 8 with the locking device is in proper adjustment, and the lock rod L is in proper working order, the locking device will always return to its proper locking position after the switch has been trailed, and will thereafter remain in its proper locking position until the switch is again trailed, or until the switch is moved away from its normal position by the mechanism B.

The circuit controller E referred to hereinbefore is located wholly within the auxiliary casing 20, and, as here shown, this circuit controller comprises a rocker arm 66 which is pivotally mounted intermediate its ends on a pin 67 secured to the casing 20. The rocker arm 66 is formed with a downwardly extending finger 67 which cooperates with a recess 68 provided in the upper face of the locking plunger 39^e, and with a cam surface 69 which cooperates with a cam 70 secured to the upper face of the locking plunger 39^e. When the locking plunger is in its locking position, the finger 67 enters the

150

recess 68, and the cam surface 69 is out of engagement with the cam 70. Under these conditions, the rocker arm 66 is rotated, by biasing means which will be described hereinafter, to its normal extreme position in which it is shown in Fig. 4. If, however, the locking plunger is moved beyond its normal locking position by the biasing springs 39^a for any reason, such for example, as would be the case if excess lost motion were developed in the linkage connecting the locking device 39 with the tie rod 8, or if the parts were improperly adjusted, the finger 67 will be forced out of the recess 68, and the rocker arm will then be rotated in a counter-clockwise direction from its normal extreme position to another extreme position. Furthermore, when the locking plunger is moved out of the notches 48 in the lock rod L in order to unlock the switch, the cam 70 cooperates with the cam surface 69 to rotate the rocker arm 66 from its normal extreme position to its other extreme position.

Pivotedly attached to the left-hand end of the rocker arm 66 is a contact operating member 71. This operating member is guided to move vertically by means of studs 73 which pass freely through holes 74 in the operating member, and is biased to an upper position by coil springs 75, one of which surrounds each stud 73 between the bottom of the case 20 and the operating member. The coil springs 75 also serve as the means referred to hereinbefore for biasing the rocker arm 66 to its normal extreme position. Secured to the upper side of the operating member 71 are two superposed insulating blocks 76 and 77 between which are clamped the free ends of a plurality of flexible contact fingers 78, here shown as four in number. Each contact finger 78 cooperates with an associated fixed contact member 79 to form a plunger lock contact 78-79. Each contact finger 78 and the associated contact member 79 are clamped to the opposite sides of an insulating block 82 by means of terminal posts 80 and 81, and the insulating block 82, in turn, is supported on lugs 83 projecting inwardly from the sides of the housing 20. Each terminal post 80 is electrically connected with the associated contact member 79, but is insulated from the associated contact finger 78, as will be apparent from an inspection of the drawings, while each terminal post 81 is insulated from both of the associated contact finger 78 and contact member 79. The parts are so proportioned that when the rocker arm 66 occupies its normal extreme position, each plunger lock contact 78-79 will be closed, but that, when the rocker arm is rotated to its other extreme position, each contact 78-79 will then become opened. It will be apparent, therefore, that the plunger lock contacts will be closed when and only when the locking device 39 occupies its normal locking position.

Associated with each plunger lock contact 78-79 is a point detector contact comprising a flexible contact finger 84 which cooperates with a fixed contact member 85. Each contact finger 84 is fastened at one end to one end of a conducting strip 86, the other end of which strip is clamped against the fixed end of the associated finger 78 to make electrical contact therewith; while each contact member 85 is secured to, and electrically connected with, the associated terminal post 81. Pivotedly mounted below the contact fingers 84 is a second contact operating member 87 (see Fig. 5) carrying a

roller 88 which at times enters a notch 89 in a point detector rod 63. The point detector rod 63 is slidably mounted in the casing 20, and is attached by means of a link 64 and a bolt member 65 with the movable rail 2 of the switch A in the usual and well known manner. The operating member 87 also carries an insulating strip 90 which cooperates with the fingers 84 in such manner that when the roller 88 is within the notch 89 in the point detector rod 63, the insulating strip 90 will be clear of the fingers 84 so that the contacts 84-85 will then all be closed, but that, when the roller is forced out of the notch 89, this strip will engage the underside of the fingers 84 and raise them to the positions in which they are out of engagement with the fixed contact members 85, thus opening the contacts 84-85. The notch 89 in the point detector rod 63 is so disposed, and the parts are so proportioned, that the roller 88 will enter the notch 89 when and only when the movable rails 2 and 2^a of the switch A occupy their normal positions, and the rail 2 is in proper engagement with the fixed rail 1.

It will be noted from an inspection of the drawings, that each plunger lock contact 78-79 and the associated point detector contact 84-85 are connected in series between the associated terminal posts 80 and 81, so that in order to complete an electrical circuit which is connected with the associated terminal posts 80 and 81, it is necessary for the locking device 39 to occupy its normal position in which the switch points are locked in their normal positions, and for the movable rail 2 to be properly closed against the fixed rail 1.

The apparatus in the form shown in Fig. 1 also comprises a signal S¹ for governing traffic moving from right to left over the switch A, and a signal S² for governing traffic moving from left to right over the switch. The primary purpose of these signals is to indicate when the switch points are properly closed and locked, and these signals may be of any suitable type and may be controlled in any suitable manner to effect this purpose. For example, when these signals are located in territory where track circuits and automatic signals are not provided, these signals will preferably be constructed and controlled in the manner indicated diagrammatically in Fig. 120.

7. Referring to Fig. 7, as here shown, the signal S¹ is a light signal, preferably of the dwarf type, provided with a yellow lamp Y and a red lamp R, and the signal S² is a similar signal provided with a green lamp G and a red lamp R. The yellow lamp Y of the signal S¹, and the green lamp G of the signal S² are provided with similar circuits, each of which includes a suitable source of current, here shown as a battery H, and a front contact 92-92^a of a relay F. The red lamps R of the signals S¹ and S² are likewise provided with similar circuits, each of which includes the battery H and a back contact 92-92^b of relay F. Relay F, in turn, is controlled by one of the plunger lock contacts 78-79 of the circuit controller E, and by the point detector contact 84-85 associated with such plunger lock contact 78-79. It will be seen, therefore, that when the movable rails of the switch A are properly closed and locked, so that the point detector and plunger lock contacts of circuit controller E are both closed, relay F will then be energized, and the lamp G of the signal S² and the lamp Y of the signal S¹ will therefore both be lighted, indicating that the switch is safe for 145 150.

traffic. If, however, the movable rails are not properly closed or locked, so that either the point detector contacts or the plunger lock contacts, or both, of the circuit controller E are open, relay F will then be deenergized, and under these conditions, the green lamp G of signal S², and the yellow lamp Y of signal S² will be extinguished, and the red lamp R of both of these signals will be lighted, indicating that the switch 10 is unsafe for traffic over the switch.

Referring now to Fig. 8, I have here shown circuits for controlling the signals S¹ and S² when they are to be used in territory where track circuits and automatic signals are provided. As here shown, the lamps Y and R of signal S¹ are controlled by a relay F¹ in exactly the same manner as they are controlled by the relay F in Fig. 7, and the lamps G and R of the signal S² are controlled by a relay F² in a similar manner. The relay F¹, in turn, is controlled by a plunger lock contact 78-79 of circuit controller E and the associated point detector contact 84-85, and also by a contact 94 over a circuit which will be obvious from an inspection of the drawings; while the relay F² is likewise controlled by a plunger lock contact 78-79 of circuit controller E, the associated point detector contact 84-85 and a contact 93. The contacts 93 and 94 may be controlled by relays not shown 30 which relays, in turn, may be controlled by conventional track circuits not shown.

With the apparatus for controlling the signals S¹ and S² arranged as shown in Fig. 8, when the movable rails 2 and 2^a of the switch A are properly closed and locked so that the plunger lock contacts 78-79 and the point detector contacts 84-85 of circuit controller E are both closed, and contact 94 is also closed, relay F¹ will be energized, and under these conditions, the lamp Y of signal S¹ will be lighted, indicating that the switch is safe for traffic, and that traffic conditions in advance of the switch are safe, and if the movable rails are not properly closed and locked, so that the plunger lock contacts 78-79, or the point detector contacts 84-85, of circuit controller E are open, or if the contact 94 is open, relay F¹ will then be deenergized, and lamp R of signal S¹ will be lighted, thus indicating that the switch is either unsafe for traffic 50 moving in the direction governed by the signal, or that traffic conditions in advance are unsafe. The operation of the portion of the apparatus associated with signal S² is similar to that just described for the signal S¹, and will be understood from an inspection of the drawings without further description.

It should be pointed out that with the plunger lock constructed as shown in Figs. 1, 3 and 4, any slack in the linkage which connects the locking device 39 with the tie rod 8 will always be taken up in the same direction due to the bias of the springs 39^a. This construction insures that the locking plunger 39^a will always be accurately located in its locking position. It also insures that if any of the connections should loosen or any of the connecting parts become disconnected or broken, the locking plunger 39^a will immediately be driven past its locking position to its extreme position by means of the biasing springs 39^a, thus opening the plunger lock contacts 78-79. It will be seen therefore that maximum protection is provided against the possibility of a false clear signal being given indicating that the switch is in proper condition for trailing, when actually the linkage by means of

which the switch is unlocked during a trailing move is out of adjustment or inoperative. Turn buckle 55 provides a convenient means for adjusting the position of the locking device 39 to its desired locking position.

Referring now to Figs. 9 and 10, I have here shown a mechanical dwarf signal S³ which may be substituted for the signals S¹ and S² and the circuit controller E shown in Fig. 1, to indicate whether the movable rails of the switch are, 85 or are not, in proper condition for train movements over the switch. This signal, in the form here shown, is adapted to be mounted on a housing 94 which is secured to the tail-like projection 19^a of the housing 19 of the operating mechanism B in place of the auxiliary casing 20 shown in Figs. 1, 3 and 4, and comprises a suitable base 95, a tubular upright 96 secured at its lower end within an opening formed in the upper part of the base 95, and a head 97 fixed to the upper end of the upright 96. An arm 98 is fixed intermediate its ends to a rocker shaft 99 journaled in the base 95, and has its one end connected by means of an adjustable link 100 with the one end of a rocker arm 101 which is pivoted intermediate its ends on a pin 102 secured to the housing 94. The rocker arm 101 is similar in all respects to the rocker arm 66 previously described in connection with signals 3 and 4, and is adapted to cooperate with the locking plunger 39^a of the operating mechanism B in the same manner as the rocker arm 66. The rocker arm 101 is biased to a normal position, in which it is shown, by means of a spring 103 interposed between the right-hand end of the arm 101 and the top of the housing 94. The end of the arm 98 opposite to that which is connected with the rocker arm 101 is connected with the lower end of a vertical link 104. The link 104 extends upwardly through the tubular upright 96, and is connected at its upper end with a crank arm 105 which is secured to a shaft 106 journaled in aligned bearings 107 formed in the head 97. The ends of the shaft 106 extend outside of the head 97 and are each provided with a semaphore arm 108. The parts are so proportioned that when the rocker arm 101 occupies its normal extreme position, the semaphore arms 108 will occupy inclined positions as shown in Fig. 8, indicating that the switch is in proper condition for traffic movements over the switch. When the rocker arm 101 is moved from its normal extreme position to its opposite extreme position, however, the semaphore arms 108 will then be rotated to a horizontal position in a manner which will be readily understood from an inspection of the drawings, thus indicating that the switch is not in proper condition for traffic movements over the switch. Each semaphore arm 108 carries two roundels 109 and 110 so disposed that the roundel 109 will be illuminated by the light from a light unit 111 when the semaphore arms occupy their inclined positions, and that the roundel 110 will be illuminated by light from the light unit 111 when the semaphore arms occupy their horizontal positions. The light unit 111 is of well known construction and is attached to the head 96 by means of a suitable bracket 112. Since the unit 111 is of well known construction, it is believed 125 to be unnecessary to describe it herein.

It will be noted that with the apparatus constructed as shown in Fig. 1, the linkage including the link 56, bell crank lever 57, and operating rod 59 for effecting the unlocking of the 135

movable points of the switch during a trailing move, is connected with the movable rails 2 and 2^a of the switch by means of a standard tie rod 8, which tie rod rigidly fastens the rails together at the point the connection is made. It is not essential, however, that the connection of this linkage with the rails should be made in this particular manner. For example, if desired, the tie rod 8 may be omitted, and the operating rod 59 may be replaced either by an operating rod 59^a, the upper end of which is secured to the movable rail 2 by means of a standard rail clip 113^a, as shown in Fig. 11, or by an operating rod 59^b, the upper end of which is secured to the movable rail 2^a by means of a rail clip 113^b, as shown in Fig. 12.

Referring now to Figs. 13, 14 and 15, as here shown, the switch is operated by a switch stand H and the locking of the switch is effected by a mechanism B¹. The switch stand H is of standard construction and comprises the usual hand-throw lever 116, and the usual crank 115 which is rotated through a suitable arc when the hand-throw lever is reversed, the crank 115 being connected with the operating rod 9 in accordance with standard practice. The operating mechanism B¹ is similar to the mechanism B shown in Figs. 3 and 4 with the following exceptions. The crank 37 and the switch-throw arm 37^a of the mechanism B have been removed from the mechanism B¹, and the hand-throw lever 30 has been replaced by a foot pedal 117. Furthermore, the hold-down member 114 of the mechanism B has been replaced by a hold-down member 118 having slots 118^a and 118^b in its lower edge which receive the bolt members 39^a and 39^b, respectively, of the locking device 39, and the springs 39^a which bias the locking device 39 to its locking position have been shortened and are arranged to bear at their right-hand ends against the hold-down member 118 adjacent the slots 118^a and 118^b. The remainder of the apparatus shown in Figs. 13, 14 and 15 is similar in all respects to that shown in Figs. 1, 3 and 4.

With the apparatus constructed as just described, the parts are so proportioned that when the movable rails occupy their normal positions in which the notches 48 in the lock rod L are in alignment with the locking plunger 39^a as shown, the springs 39^a will move the locking device 39 to its normal locking position. When the locking device 39 occupies its normal locking position, the end member 39^a will engage the lugs 42 and 43 on the motion plate and will hold the motion plate in the extreme position shown, thus holding the foot pedal in its normal raised position.

When it is desired to reverse the switch, the foot pedal 117 is first depressed, which unlocks the movable rails of the switch in a manner which will be readily understood from the foregoing description and from an inspection of the drawings without further description. The hand-throw lever 116 of the switch stand H is then operated from the extreme position shown to its opposite extreme position. As soon as the movable rails have started to move, the resultant movement of the tie rod 8 will operate the linkage which connects the tie rod with the locking device 39 a sufficient amount to cause the locking device to be positively held in the position in which the locking plunger is out of engagement with the lock rod, and the foot pedal 117 may then be released. The linkage will then

continue to hold the locking device in a position in which the locking plunger is out of engagement with the locking device until the switch is restored to its normal position. When it is desired to do this, the hand-throw lever 116 of the switch stand H is restored to the position shown. As soon as the movable rails 2 and 2^a reach their normal extreme positions, so that the notches 48 in the lock rod L are in alignment with the locking plunger 39^a, the spring 39^a will cause the locking device 39 to move to its locking position with a snap action, which movement, in turn, will cause the motion plate 26 and foot pedal 117 to return to their normal positions.

When a train trails the switch, the apparatus will operate in substantially the same manner as the apparatus shown in Fig. 1, and it is believed, therefore, that this operation will be readily understood from the drawings without describing it in detail.

Referring now to Figs. 16 and 17, in the modified form of my invention here shown, a pair of rail clips 118^c are secured to the base of the rail 1, and each of these clips is provided with a laterally extending pin or bolt 119 upon which a short link or arm 120 is pivoted. The free ends of the arms 120 are free to swing in a short arc, the length of which arcs is limited by means of lugs 121 and 122 fixed on the associated rail clip 118^c. Supported on the free ends of the arms 120 is a treadle bar 123 which treadle bar lies adjacent the head of the rail 1 and is adapted, when the links occupy the positions in which they engage the associated stops 122 as shown, to project above the rail head, this being the normal position of the treadle bar when the switch occupies its normal position. A link 124 is pivotally attached at one end to the left-hand arm 120 in such manner that when the treadle bar 123 is depressed, this link will move toward the left, and the free end of this link is connected with one end of a lever 125 which is pivoted intermediate its ends on a fixed pivot 126. The other end of the lever 125 is connected with the locking device 39 of the operating mechanism B by means of a link 127, the turn buckle 55, and the plunger bolt 54. The remainder of the apparatus shown in Figs. 16 and 17 is similar in all respects to that shown in Figs. 1, 3 and 4.

The operation, as a whole, of the apparatus in the modified form just described is as follows: As shown in the drawings, the hand-throw lever 30 is moved to its normal extreme position, and the movable rails of the switch are therefore moved to their normal extreme positions in which positions the movable rail 2 engages the fixed rail 1 and the movable rail 2^a is spaced from the fixed rail 1^a. Under these conditions, the notches 48 in the lock rod L are in alignment with the locking plunger 39^a of the locking device 39, and the locking device 39 is therefore moved to its locking position by the springs 39^a, thus locking the switch points in their normal extreme positions. The parts are so proportioned that when the locking device occupies its locking position, the end member 39^a of the locking device will engage the head of the plunger bolt 54 and will exert a force on this bolt which force acts through the linkage connecting the plunger bolt with the treadle bar 123 to hold the treadle bar in its raised position in which the supporting arms 120 engage the stop 122.

I will now assume that the hand-throw lever 130

30 is moved from the normal position shown to its reverse position, to reverse the switch. During the first part of this movement, the switch points will not be moved for the reasons previously described in connection with Fig. 1, but the resultant movement of the motion plate 26 will cause the lugs 42 and 43 on the motion plate to engage the locking device 39 and move the locking device to the position in which the locking plunger 39^e is out of engagement with the notches 48 in the lock rod L, thus unlocking the switch. As the locking device 39 is moved to the position in which the locking plunger 39^e is out of engagement with the notches 48 in the lock rod L, the force tending to hold the treadle bar 123 in its raised position is gradually removed, and the treadle device therefore moves, under the influence of gravity, to its depressed position. During the intermediate part of the movement of the hand-throw lever 30, the movable rails of the switch are reversed in the manner previously described in connection with Figs. 1, 3 and 4, and during the final part of the movement of the hand-throw lever, the movable rails are locked in their reverse positions due to engagement of the roller 34 on the crank 37 (see Fig. 3) with the straight portion at the right-hand end of the cam slot 28 in the motion plate 26.

30 When it is desired to restore the switch to its normal position, the hand-throw lever 30 is restored to the position shown. Under these conditions, as soon as the movable rails 2 and 2^a have been moved toward their normal positions a short distance, the locking plunger 39^e of the locking device 39 will be moved into engagement with the edge of the lock rod L by the springs 39^a, and will subsequently be held in engagement with the edge of the lock rod until the movable rails have reached the positions in which the notches 48 in the lock rod align with the locking plunger 39^e, at which time the stored energy of the springs 39^a will move the locking device to its locking position. When the locking device is moved to its locking position, the linkage which connects the locking device with the treadle bar 123 will move the treadle bar to its raised position. The parts will then be restored to the positions shown.

50 I will now assume that the movable rails of the switch are in their normal positions and are locked in these positions, and that a train trails the switch. Under these conditions, before the wheels of the train will have moved far enough to exert a force on the movable rails tending to move the rail 2 away from the rail 1, the leading wheel of the train running on rail 1 will depress the treadle bar 123, which will act through the linkage which connects the treadle bar with the locking device, to move the locking device to the position in which the locking plunger 39^e is out of engagement with the lock rod L, thus unlocking the switch. The treadle bar is so positioned and of such length, that after it has once been depressed it will be held depressed by at least one of the wheels of the car until the movable rails have been forced away from their normal positions, after which the buffering device D will act to prevent the movable rails from returning to the positions in which the locking plunger can enter the notches 48 in the lock rod L, until the train has completely passed the switch. When the train has completely passed the switch, and the rails have been returned to their normal positions by the spring 15 of the

spring connecting rod C, the springs 39^a will restore the locking device 39 to its locking position, which will cause the treadle bar 123 to return to its normal position.

It should be pointed out that with the apparatus constructed as shown in Figs. 16 and 17, any lost motion in the linkage connecting the locking device 39 with the treadle bar 123 will be taken up by the springs 39^a in substantially the same manner as any lost motion in the linkage connecting the locking device 39 with the tie rod 8 in Fig. 1 is taken up by the springs 39^a, and that any excess wear in this linkage or any improper adjustment of the parts will be detected by the circuit controller E.

Referring now to Fig. 18, in the modified form of my invention here shown, the movable rails 2 and 2^a of the switch A are connected together solely by means of two spring connecting rods C¹ and C² embodying my invention. The connecting rod C¹ is illustrated in section in Fig. 19, and as here shown, comprises a tubular casing 128 provided intermediate its ends with an integral apertured projecting lug 128^a. The one end of the casing 128 is partly closed by an integral end plate 128^b which is pierced by an axially disposed hole 128^c, and the other end of the casing 128 is partly closed by an end cap 129 formed with an axially disposed hole 129^a. A rod 130 extends into the casing 128 through the hole 128^c in the end plate 128^b, and is provided at its inner end with a cylindrical member 131 which is adapted to slide freely within the casing. Surrounding the rod 130 between the end plate 128^b and the member 131 is a compressed coil spring 132 which biases the rod to the position in which the member 131 engages a cylindrical member 133. The cylindrical member 133 is slidably mounted within the casing 128 between the member 131 and the end cap 129, and is attached at its inner end to a rod 134 which extends outwardly with some clearance through the hole 129^a in the end cap 129. The outer end of the rod 130 is secured to the movable rail 2^a of the switch by means of a bar 135 and a standard rail clip 136, and the outer end of the rod 134 is secured to the movable rail 2 by means of a turn buckle 137, a bar 138, and a rail clip 139. The connecting rod C² is similar in all respects to the connecting rod C¹ with the exception that the enclosing casing of the connecting rod C² is not provided with a lug 128^a.

It should be pointed out that with the movable rails 2 and 2^a of the switch A connected together by the spring connecting rods C¹ and C² just described, the rails are positively prevented from moving closer together than the distance for which they are adjusted, but if a sufficient lateral force is exerted on the movable rail which is not engaging the associated fixed rail in either position of the switch, in a direction to move such movable rail toward the associated fixed rail, as is the case when a train trails the switch, the springs 132 of the connecting rods C¹ and C² will become compressed, and will permit such movable rail to move toward the associated fixed rail.

A throw-rod 140 is secured, near its upper end, to the lug 128^a on the casing 128 of the spring connecting rod C¹ by means of nuts 140 which are screwed onto the rod on opposite sides of the lug, and this rod is connected at its lower end with the switch operating mechanism B by means of an operating rod 9, thus operatively connecting the movable rails of the

switch with the operating mechanism B. The parts are so proportioned that movement of the hand-throw lever 30 of the mechanism B to either extreme position will move the movable 5 rails to their corresponding extreme positions.

The lock rod L of the mechanism B, as here shown, is connected with the movable rail 2 only, this connection being effected by means of a point bracket 141. The lock rod is so adjusted 10 that the notches 48 therein will align with the locking plunger 39^a of the locking device 39 when and only when the rail 2 occupies its normal position in which it is shown in the drawings.

15 The point detector rod 63 of the mechanism B is also connected with the movable rail 2 only, this connection being effected by the link 64, bolt member 65 and bracket 141. The point detector rod is so adjusted that the notch 89 20 therein will align with the roller 88 on the operating member 87 of the circuit controller E when and only when the rail 2 is in its normal position as shown.

25 The locking device 39 of the mechanism B, as here shown, is operatively connected with the movable rail 2^a by means of linkage which is similar to that shown in Fig. 12 except that the link 58 shown in Fig. 12 has been replaced by a shorter link 58^a, in order to permit the linkage 30 to be connected with the rail 2^a nearer to the point of the rail. This linkage is so adjusted that when the rails 2 and 2^a are in their normal positions, and the locking device 39 has been moved to its locking position by the biasing 35 springs 39^a, the head of the plunger bolt 54 will engage the left-hand side of the end member 39^d of the locking device 39 (see Fig. 4), and will prevent the biasing of springs 39^a from moving the locking device beyond its locking position.

40 The piston rod 50 of the buffering device D is connected, by means of the adjustable link 49, with the bar 135 associated with the spring connecting rod C¹, and the cam shaft 51 of buffering device D is connected with the throw-rod 45 140 by means of the crank 52 and the link 53.

As shown in the drawings, the hand-throw lever 30 of the locking mechanism B occupies its full line or normal position, and the movable rails are therefore held in their normal positions. 50 The notch 48 in the lock rod L therefore aligns with the locking plunger 39^a of the locking device 39, and the locking device is therefore moved to its locking position by means of the springs 39^a, thus locking the rail 2 in its normal position. 55 It will be noted, however, that the movable rail 2^a is unlocked.

When it is desired to reverse the switch, the hand-throw lever 30 of the mechanism B is operated from its normal or full line position to its dotted line position, and when it is desired to subsequently restore the switch to the position shown, the hand-throw lever is moved from its dotted line position to its full line position. In either instance, the apparatus will function in 65 substantially the same manner as was previously described in connection with Fig. 1, and it is therefore believed that this operation will be understood from the foregoing description and from an inspection of the drawings without further description.

When the parts are in the positions shown, and a train trails the switch, rail 2^a is engaged by, and pushed toward the rail 1^a by the leading wheel of the car running on rail 2^a (this movement of the rail being permitted by the spring

connecting rods C¹ and C²) before the wheel on the opposite end of the same axle as the wheel on rail 2^a engages the movable rail 2. This movement of the rail 2^a is transmitted to the locking device 39 through the linkage connecting this rail with the locking device, thus withdrawing the locking device from its locking position to the position in which the locking plunger 39^a is out of engagement with the notches 48 in the lock rod L, and hence unlocking the switch. As a result, when the wheel on rail 1 does engage the movable rail 2, the movable rail 2 will be unlocked, and the movable rail will therefore be free to move away from the rail 1. After the rail 2 has once been unlocked, the combined action of the buffering device D and the wheels of the car will prevent the rail 2 from again becoming locked until after the train has completely passed the switch. When this has happened, the movable rails will be returned to their normal positions by the springs 132 of the spring connecting rods C¹ and C², and when the rails have reached their normal positions, the locking device 39 will be restored to its locking position by the bias of the 100 springs 39^a.

It should be noted that with the apparatus constructed as shown in Fig. 18, if the movable rail 2^a should fail to return to its normal position for any reason after the switch has been 105 trailed, the linkage which connects this rail with the locking device 39 will prevent the locking device from returning to its normal position, and an indication of the fact that the switch is not in proper condition for traffic over the switch 110 would therefore be given by the circuit controller E.

Referring now to Fig. 20, the apparatus here shown is similar in all respects to that shown in Fig. 1, except for the means for operating the locking device 39 to withdraw the locking plunger 39^a from engagement with the notches 48 in the lock rod L when a train trails the switch. As here shown, this means comprises an operating bar 142 which is located adjacent the heel of the switch, and which extends along the rail 2^a for several feet in either direction from the heel of the switch, the actual length of this operating bar being dependent upon the length of the switch, the type of traffic over 120 the switch, etc. The operating bar 142 is mounted for parallel movement toward or away from the rail 2^a by means of a plurality of arms 143 which are pivotally attached at one end to the operating bar, and at the other end to a stationary plate 144 secured to the cross ties 4. A pair of compression springs 145 are interposed between the operating bar and suitable thrust members 146 secured to the plate 144, and serve to bias the operating bar to its normal position in which it engages the rail 2^a, as shown in the drawings. The ends of the operating bar are flared outwardly as shown to facilitate the movement of the flange of a car wheel between the operating bar and the rail 2^a, it 140 being obvious that when the flange of a car wheel is between the operating bar and the rail 2^a, the operating bar will be moved parallel to, and laterally away from, the rail 2^a in opposition to the bias of the compression springs 145. 145 Formed integral with one of the arms 143, and extending at an angle thereto, is an arm 147, the free end of which is pivotally connected with the previously described operating rod 59, thus operatively connecting the operating bar with 150

the locking device 39 of the switch operating mechanism B. The parts are so proportioned that when the switch A occupies its normal position and the operating bar 142 occupies the 5 position to which it is biased, the linkage which connects the operating bar with the locking device 39 will act to hold the locking device in its normal locking position, but that, when the operating bar is forced away from the rail 2^a 10 by the wheel of a car to what I shall term its "operated" position, the linkage which connects the locking device with the operating bar will then act to move the locking device to the position in which the locking plunger 39^e of the 15 locking device 39 is out of engagement with the notches 48 in the lock rod L, thus unlocking the switch A. As pointed out above, the remainder of the apparatus shown in Fig. 20 is similar to that shown in Fig. 1.

20 With the apparatus constructed as shown in Fig. 20 when the switch is operated by the hand-throw lever 30, the apparatus functions in substantially the same manner as was previously described in connection with Fig. 1, with the 25 exception that under these conditions the plunger bolt 54 remains stationary. It is believed, therefore, that the operation of the apparatus under these conditions will be readily understood from the foregoing and from an inspection 30 of the drawings without further description.

When the switch occupies its normal position in which it is shown in the drawings, and a train trails the switch, each time a truck on a car passes the operating bar 142, the wheels of the truck will force the operating bar away from the rail 2^a to its operated position, and the parts are so proportioned that the wheels on the truck will then continue to hold the operating bar in its operated position until after the wheels of the truck have moved far enough toward the point of the switch to exert a force on the movable rails which is greater than the opposing force of the spring in the spring connecting rod C. When the operating bar is moved to its operated position, the locking device 39 of the operating mechanism B is moved to the position in which the locking plunger 39^e is disengaged from the recesses 48 in the lock rod L (see Figs. 3 and 4), so that the movable 35 rails are then unlocked. It will be seen, therefore, that when each truck of a car reaches the position in which a force is exerted on the movable rails which is greater than the opposing force of the spring in the spring connecting rod, the movable rails will be moved to their reverse 40 positions in substantially the same manner as if no lock were provided for the switch. When the movable rails occupy any position but their full normal position, the notches 48 in the lock rod L are out of alignment with the locking plunger 39^e, and it will be apparent, therefore, 45 that when the movable rails have once been unlocked, they will remain unlocked until the switch points have been returned to their full normal positions and no wheel of a car is engaging the operating bar 142. Due to the buffering device D, the movable rails will not return to their normal positions as long as the train which is trailing the switch keeps moving, so that when the rails have once been unlocked by a train which keeps moving while it is trailing the switch, the movable rails will remain unlocked until the train has completely passed the switch. In the event that a train which has started to trail the switch stops while the train

is trailing the switch, if the wheels of the train are then in such a position that none of the wheels are engaging either the treadle bar or the movable rails, thus permitting the spring 80 in the spring connecting rod C to return the rails to their normal positions and the springs 39^a to return the locking device 39 to its locking position, when the train subsequently starts to complete the trailing movement, the first truck to pass the operating bar 142 will cause the 85 movable rails to again become unlocked, and during the remainder of the trailing movement the points will remain unlocked for the reasons pointed out above. If the train should stop in a position, however, in which the wheels of the 90 train are engaging either the switch points or the operating bar, the switch will remain unlocked for reasons which will clearly be apparent from the foregoing. As soon as a train which has been trailing the switch is completely past the switch, the movable rails will be returned to their full normal positions by the spring 15 of the spring connecting rod C, and the springs 39^a will restore the locking device 39 to its locking position, thus relocking the movable rails of 100 the switch. The parts will then all be restored to their normal positions in which they are shown in the drawings.

Throughout the foregoing description it has been stated that when a train is trailing the 105 switch, the locking plunger 39^e will become completely withdrawn from engagement with the notches 48 in the lock rod L to unlock the movable rails of the switch before a sufficient force is developed at the point of the closed rail to 110 overcome the opposing force of the spring in the spring connecting rod. While this is the preferred proportioning of the parts, it is not absolutely essential to my invention. For example, the mechanism as described herein 115 would be workable if the locking plunger did not become entirely withdrawn from the notches in the lock rod before the point of the closed movable rail tended to open, but remained in engagement with the notches in the 120 lock rod for a time after the point of the closed rail tended to open, and assisted the spring in the spring connecting rod in holding the point of the closed rail closed; it being essential, of course, that the locking plunger should be completely withdrawn from engagement with the notches in the lock rod before sufficient force is 125 exerted on the movable rails to damage the lock rod, or the rails, or the operating mechanism, or all three.

Although I have herein shown and described only a few forms of railway switch operating apparatus embodying my invention, it is understood that various changes and modifications may be made therein within the scope of the 135 appended claims without departing from the spirit and scope of my invention.

Having thus described my invention, what I claim is:

1. The combination with a railway switch comprising a movable rail and a device for operating said movable rail connected with the rail through resilient means, of means for normally rigidly locking said movable rail in one extreme position, and means mechanically actuated by the forces which are developed in said movable rail when a train is trailing the switch for unlocking the rail.

2. In combination, a spring switch, a tie rod connecting the movable rails of the switch at 140

- a point approximately half way between the heel and the point of the switch, means for rigidly locking the movable rails of the switch in one extreme position, and means connected 5 with and actuated by said tie rod for unlocking the movable rails when a train trails the switch.
3. In combination, a spring switch, means for rigidly locking the movable rails of the switch in one extreme position, and means connected 10 with one of the movable rails at a point approximately half way between the heel and the point of the switch and responsive to the lateral bending of the rail which takes place when a train trails the switch for unlocking the movable rails.
4. In combination, a switch comprising a pair of movable rails, means including a spring for operating the movable rails to their extreme positions, means for locking the movable rails in 15 one of their extreme positions, and means connected with one of the movable rails and responsive to the lateral bending of such one rail which takes place when a train trails the switch before a sufficient force is developed at the point 20 of the rail to overcome the opposing force of said spring for unlocking the movable rails.
5. In combination, a railway switch, means including a spring for moving the movable rails of said switch to their normal and reverse positions, a lock rod connected with the movable rails for movement therewith and provided with 25 a notch, a locking plunger adapted to enter the notch in said lock rod when and only when the movable rails occupy their normal 30 positions, means for biasing said locking plunger to the position in which it enters the notch in said lock rod, a tie rod connected with the movable rails at a point approximately midway between the heel and the point of the 35 switch, and linkage connecting said tie rod with said locking plunger so arranged that when a train trails the switch the lateral bending of the movable rails which takes place before a force is developed at the points of these 40 rails which is sufficient to overcome the opposing force of said spring will cause said locking plunger to be withdrawn from the notch in said lock rod.
6. In combination, a railway switch, means including a spring for moving the movable rails of said switch to their normal and reverse positions, a lock rod connected with the movable rails for movement therewith and provided with 45 a notch, a locking plunger adapted to enter the notch in said lock rod when and only when the movable rails occupy their normal 50 positions, means for biasing said locking plunger to the position in which it enters the notch in said lock rod, a tie rod connected with the movable rails at a point approximately midway between the heel and the point of the switch, linkage connecting said tie rod with said locking plunger so arranged that when a train trails the switch the lateral bending of the movable rails which takes place before a force is developed at the points of these 55 rails which is sufficient to overcome the opposing force of said spring will cause said locking plunger to be withdrawn from the notch in said lock rod, and a buffering device connected with the rails to retard the return movement of the rails to their normal positions after they have been forced away from these positions by the wheels of a train which is trailing the switch.
7. In combination, a railway switch compris- 75
- ing two movable rails and two fixed rails, means including a spring connecting rod for moving the movable rails to their normal and reverse positions, a lock rod connected with the movable rails for movement therewith and provided with a notch, a locking plunger adapted to enter the notch in said lock rod when and only when the switch occupies its normal position to lock the movable rails in this position of the switch, said locking plunger being movable within said notch to an extreme position which is beyond the normal locking position, a spring for biasing said locking plunger to said extreme position, a tie rod connecting the movable rails at a point approximately midway between the heel and the point of the switch, linkage connecting said locking plunger with said tie rod so adjusted that when said switch occupies its normal position said linkage will prevent said locking plunger from moving beyond the proper locking position, and a circuit controller for indicating when said locking plunger occupies its locking position.
8. In combination, a railway switch comprising two movable rails and two fixed rails, means including a spring connecting rod for moving the movable rails to their normal and reverse positions, a lock rod connected with the movable rails for movement therewith and provided with a notch, a locking plunger adapted to enter the notch in said lock rod when and only when the switch occupies its normal position to lock the movable rails in this position of the switch, said locking plunger being movable within said notch to an extreme position which is beyond the normal locking position, a spring for biasing said locking plunger to said extreme position, a tie rod connecting the movable rails at a point approximately midway between the heel and the point of the switch, linkage connecting said locking plunger with said tie rod so adjusted that when said switch occupies its normal position said linkage will prevent said locking plunger from moving beyond the normal locking position, a point detector rod connected with one movable rail, and means controlled by said locking plunger and said point detector rod for indicating when the movable rails are properly locked and the parts are properly adjusted for train movements over the switch.
9. In combination, a railway switch compris- 125
- ing two movable rails and two fixed rails, means including a spring connecting rod for moving the movable rails to their normal and reverse positions, a lock rod connected with the movable rails for movement therewith and provided with a notch, a locking plunger adapted to enter the notch in said lock rod when and only when the switch occupies its normal position to lock the movable rails in this position of the switch, said locking plunger being movable within said notch to an extreme position which is beyond the normal locking position, a spring for biasing said locking plunger to said extreme position, a tie rod connecting the movable rails at a point approximately midway between the heel and the point of the switch, and linkage connecting said locking plunger with said tie rod so constructed and so adjusted that when said switch occupies its normal position said linkage will prevent said locking plunger from moving beyond its normal locking position and that when a train trails the switch said linkage will act to withdraw said locking plunger from the notch in said lock rod to unlock the switch.
10. In combination, a railway switch compris- 150

ing two movable rails and two fixed rails, means including a spring connecting rod for moving the movable rails to their normal and reverse positions, a lock rod connected with the movable 5 rails for movement therewith and provided with a notch, a locking plunger adapted to enter the notch in said lock rod when and only when the switch occupies its normal extreme position to lock the movable rails in this position of the 10 switch, said locking plunger being movable within said notch to an extreme position which is beyond the normal locking position, a spring for biasing said locking plunger to said extreme position, a tie rod connecting the movable rails 15 at a point approximately midway between the heel and the point of the switch, linkage connecting said locking plunger with said tie rod so constructed and so adjusted that when said switch occupies its normal position said linkage 20 will prevent said locking plunger from moving beyond the normal locking position and that when a train trails the switch said linkage will act to withdraw said locking plunger from the notch in said lock rod to unlock the switch, and 25 indication means controlled by said locking plunger for indicating when said locking plunger occupies its normal locking position.

11. In combination, a railway switch comprising two movable rails and two fixed rails, means 30 including a spring connecting rod for moving the movable rails to their normal and reverse positions, a lock rod connected with the movable rails for movement therewith and provided with a notch, a locking plunger adapted to enter the 35 notch in said lock rod when and only when the switch occupies its normal position to lock the movable rails in this position of the switch, said locking plunger being movable within said notch to an extreme position which is beyond the normal locking position, a spring for biasing said 40 locking plunger to said extreme position, and linkage connecting said locking plunger with one of the movable rails at a point approximately half way between the heel and the point of the 45 switch, said linkage being so constructed and so adjusted that when said switch occupies its normal position said linkage will prevent said locking plunger from moving beyond its normal locking position and that when a train trails the 50 switch said linkage will act to withdraw said locking plunger from the notch in said lock rod to unlock the switch.

12. In combination, a casing provided with two slots extending at right angles, a railway 55 switch lock rod slidably mounted in the one slot and provided with a notch which is adapted to receive a locking plunger slidably mounted within the other slot, said locking plunger being movable within said notch to an extreme position which 60 is beyond its normal locking position, a rocker arm pivotally mounted adjacent said locking plunger and biased to one position, and means provided on said rocker arm and cooperating with means provided on said locking plunger for rotating said rocker arm to another extreme 65 position when said locking plunger is moved from its normal locking position to any other position.

13. In combination, a casing provided with 70 two slots extending at right angles, a railway switch lock rod slidably mounted in the one slot and provided with a notch which is adapted to receive a locking plunger slidably mounted within the other slot, said locking plunger being 75 movable within said notch to an extreme posi-

tion which is beyond its normal locking position, a rocker arm pivotally mounted in said casing adjacent said locking plunger and biased to one position, means provided on said rocker arm and cooperating with means provided on said locking plunger for rotating said rocker arm to another extreme position when said locking plunger is moved from its normal locking position to any other position, and a circuit controller operated by said rocker arm.

14. In combination, a casing provided with two slots extending at right angles, a railway switch lock rod slidably mounted in the one slot and provided with a notch which is adapted to receive a locking plunger slidably mounted within the other slot, said locking plunger being movable within said notch to an extreme position which is beyond its normal locking position and provided in its upper face with a recess, a cam secured to the upper face of said locking plunger, a rocker arm pivotally mounted above said locking plunger and biased to one position, said rocker arm being provided with a finger which cooperates with said recess and with a cam surface which cooperates with said cam; the parts being so proportioned that when said locking plunger occupies its normal locking position said finger will enter said recess and said cam surface will be out of engagement with said cam, but that if said plunger is moved from its normal locking position in one direction said finger will be forced out of said recess and will cause said rocker arm to be rotated from the position to which it is biased to another position and if said plunger is moved from its normal locking 100 position in the other direction said cam surface will ride up on said cam and rotate said rocker arm from the position to which it is biased to said other position; and a circuit controller controlled by said rocker arm.

15. In combination with a railway switch comprising two movable rails and two fixed rails, an operating mechanism for said switch comprising a casing, a motion plate mounted in said casing for reciprocation between two extreme 110 positions, means for reciprocating said motion plate between its two extreme positions, means including a spring connecting rod for operatively connecting said motion plate with said movable rails in such manner that movement 115 of said motion plate from its one extreme position to the other will move said switch from its normal to its reverse position and vice-versa, a lock rod secured to the movable rails of said switch for movement therewith and extending 120 into said casing and provided within said casing with a notch, a locking device slidably mounted in said casing above said motion plate, said locking device comprising two spaced parallel 125 side members connected by two parallel end members, one of which end members is provided with a hole, a locking plunger secured to the other end member and adapted to enter the notch in said lock rod when and only when the switch occupies its normal position, said 130 locking device being movable when said locking plunger is within said notch to an extreme position which is beyond its normal locking position, two bolt members secured to said two end members and extending parallel to said two side 135 members in spaced relation thereto, a pair of lugs on said motion plate each provided with a hole which slidably receives one of said bolt members, two springs one on each bolt member between said other end member and the asso- 140

16. In combination with a railway switch comprising two movable rails and two fixed rails, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to the other will move said switch from its normal to its reverse position and vice-versa, a lock rod secured to the movable rails of said switch for movement therewith and extending into said casing and provided within said casing with a notch, a locking device slidably mounted in said casing above said motion plate, said locking device comprising two spaced parallel side members connected by two parallel end members, one of which end members is provided with a hole, a locking plunger secured to the other end member and adapted to enter the notch in said lock rod when and only when the switch occupies its normal position, said locking device being movable when said locking plunger is within said notch to an extreme position which is beyond its normal locking position, two bolt members secured to said two end members and extending parallel to said two side members in spaced relation thereto, a pair of lugs on said motion plate each provided with a hole which slidably receives one of said bolt members, two springs one on each bolt member between said other end member and the associated lug for biasing said locking device to said extreme position, said lugs being so positioned on said motion plate and the parts being so proportioned that when said motion plate is moved from its one extreme position to its other extreme position to move said switch from its normal to its reverse position said lugs will engage said one end member and will move said locking device to a position in which said locking plunger is out of said notch in said lock rod before the movable rails start to move, a plunger bolt extending through the hole in said one end member with some clearance and provided on its inner end with a head which is larger than said hole, a tie rod connected with the movable rails of said switch approximately midway between the heel and the point of the switch, and linkage connecting said plunger bolt with said tie rod so constructed and so adjusted that when the switch occupies its normal position the head of said plunger bolt will engage said one end member and will hold said locking device in its normal locking position and that when a train trails the switch said bolt member will then engage said one end member and move said locking device to the position in which said locking device occupies its normal locking position. 90 95 100 105 110 115 120 125 130 135 140 145 150

locking plunger is withdrawn from said notch in said lock rod.

18. In combination, a main casing provided with two slots extending at right angles, a railway switch lock rod slidably mounted in one slot and provided with a notch which is adapted to receive a locking plunger slidably mounted within the other slot, said locking plunger being movable within said notch to an extreme position which is beyond its normal locking position and provided in its upper face with a recess, a cam secured to the upper face of said locking plunger, an auxiliary casing secured to said main casing and communicating with said main casing adjacent said lock rod and said locking plunger; a rocker arm pivotally mounted in said auxiliary casing above said locking plunger and provided on one end with a downwardly extending finger which cooperates with said recess and with a cam surface which cooperates with said cam, the parts being so proportioned that when said locking plunger occupies its normal locking position said finger will enter said recess and said cam surface will be out of engagement with said cam but that if said plunger is moved from its normal locking position in one direction said finger will be forced out of said recess and will rotate said rocker arm from the position to which it is biased to another position and if said locking plunger is moved from its normal locking position in the other direction said cam surface will ride up on to said cam and rotate said rocker arm from the position to which it is biased to said other position, a first contact operating member pivotally attached to the opposite end of said rocker arm from said finger and said cam surface and biased to an upper position, an insulating block secured to said auxiliary casing, a contact comprising a first fixed contact member and a first flexible contact finger, said first contact member and said first contact finger being secured to the upper and lower sides respectively of said insulating block by means of a pair of terminal posts in such manner that one terminal post is electrically connected with said contact member but is insulated from said first contact finger and the other terminal post is insulated from both said conducting member and said first contact finger, two superposed insulating blocks secured to said first operating member and having the free end of said flexible contact finger clamped therebetween, a conducting strip clamped at one end against said conducting strip by means of said terminal posts and insulated from said terminal posts, a second flexible contact finger secured to the free end of said conducting strip and cooperating with a second fixed contact member secured to and electrically connected with said other terminal post, a detector rod extending into said casing and provided with a notch, a second contact operating member pivotally attached to said casing and provided with a roller which cooperates with said notch, and an insulating strip secured to said second operating member and cooperating with said second flexible contact finger.
19. In combination with a locking plunger adapted to enter a notch in a railway switch lock rod to lock the movable rails of the switch in one position, a rocker arm pivotally mounted adjacent said locking plunger, means controlled by said locking plunger for moving said rocker arm to one position when said locking plunger is within said notch in said lock rod and to

another position when said locking plunger is withdrawn from said notch, a semaphore arm, and linkage connected with said semaphore arm and with said rocker arm in such manner that said semaphore arm will occupy one position or another according as said rocker arm occupies its one position or its other position. 80

20. In combination, a locking plunger movable from an intermediate locking position to two extreme positions and provided in its upper face with a recess, a cam secured to the upper face of said locking plunger, a rocker arm pivotally mounted above said locking plunger and provided with a finger which cooperates with said recess to move said rocker arm from one extreme position to another extreme position when said locking plunger is moved from its normal locking position in one direction, said locking plunger also being provided with a cam surface which cooperates with said cam to move said rocker arm from said one extreme position to said other extreme position when said locking plunger is moved from its normal locking position in the other direction, means for biasing said rocker arm to said one extreme 100 position, a semaphore arm, and linkage connecting said rocker arm and said semaphore arm so constructed and so adjusted that said semaphore arm will occupy one position or another according as said rocker arm occupies its one 105 position or its other position.

21. In combination, a switch operating mechanism casing provided at one end with a slot, a locking plunger slidably mounted in said slot for cooperation with a railway switch lock rod, 110 a housing secured to said casing above said locking plunger and communicating with said casing, a dwarf signal base secured to said housing and provided in its upper end with a hole, a tubular upright secured to said housing within said hole, 115 a head secured to the upper end of said upright, a lever journaled intermediate its ends in said base, a link pivotally attached to one end of said lever and extending upwardly through said upright into said head, a horizontal shaft journaled in said head and carrying an arm which is connected with the upper end of said link, a semaphore arm secured to the outer end of said shaft, a rocker arm journaled in said housing and connected at one end with the other end 125 of said lever, and means provided on said rocker arm and cooperating with means provided on said locking plunger for moving said rocker arm to one position or another according as said locking plunger occupies or does not occupy its 130 locking position.

22. The combination with a railway switch comprising two movable rails and two fixed rails and an operating device for said switch connected with the movable rails by means including 135 a spring connecting rod, of a casing, a plate mounted in said casing for reciprocation between two extreme positions, means for reciprocating said plate between its two extreme positions, a lock rod secured to the movable rails 140 of said switch for movement therewith and extending into said casing and provided within said casing with a notch, a locking device slidably mounted in said casing above said motion plate, said locking device comprising two spaced 145 parallel side members connected by two parallel end members, one of which end members is provided with a hole, a locking plunger secured to the other end member and adapted to enter the notch in said lock rod when and only when 150

the switch occupies its normal position, said locking device being movable when said locking plunger is within said notch to an extreme position which is beyond its normal locking position, two bolt members secured to said two end members and extending parallel to said two side members in spaced relation thereto, a pair of lugs on said motion plate each provided with a hole which slidably receives one of said bolt members, a hold down member secured to said casing above said lock rod and provided with two slots which receive said bolt members between said lugs and said other end member, two compressed coil springs one on each bolt member between said other end member and said hold down member for biasing said locking device to said extreme position, said lugs being so positioned on said motion plate and the parts being so proportioned that when said plate is moved from its one extreme position to its other extreme position said lugs will engage said one end member and will move said locking device to a position in which said locking plunger is out of said notch in said lock rod, a plunger bolt extending through the hole in said one end member with some clearance and provided on its inner end with a head which is larger than said hole, a tie rod connected with the movable rails of said switch approximately midway between the heel and the point of the switch, and linkage connecting said plunger bolt with said tie rod so constructed and so adjusted that when the switch occupies its normal position the head of said plunger bolt will engage said one end member and will hold said locking device in its normal locking position and that when a train trails the switch said bolt member will then engage said one end member and move said locking device to the position in which said locking plunger is withdrawn from said notch in said lock rod. 24. The combination with a railway switch comprising two movable rails and two fixed rails and an operating device for said switch connected with the movable rails by means including a spring connecting rod, of a casing, a plate mounted in said casing for reciprocating between two extreme positions, rack teeth on the upper face of said plate, a shaft journalled in said casing and provided with a gear segment which meshes with said rack teeth, a foot pedal secured to said shaft, a lock rod secured to the movable rails of said switch for movement therewith and extending into said casing and provided within said casing with a notch, a locking device slidably mounted in said casing above said plate, said locking device comprising two spaced parallel side members connected by two parallel end members, one of which end members is provided with a hole, a locking plunger secured to the other end member and adapted to enter the notch in said lock rod when and only when the switch occupies its normal position, said locking device being movable when said locking plunger is within said notch to an extreme position which is beyond its normal locking position, two bolt members secured to said two end members and extending parallel to said two side members in spaced relation thereto, a pair of lugs on said motion plate each provided with a hole which slidably receives one of said bolt members, a hold down member secured to said casing above said lock rod and provided with two slots which receive said bolt members between said lugs and said other end member, two compressed coil springs one on each bolt member between said other end member and said hold down member for biasing said locking device to said extreme position, said lugs being so positioned on said plate and the parts being so proportioned that when said plate is moved from its one extreme position to its other extreme position said lugs will engage said one end member and will move said locking device to a position in which said plunger bolt is out of said notch in said lock rod, a plunger bolt extending through the hole in said one end member with some clearance and provided on its inner end with a head which is larger than said hole, and linkage connecting said plunger bolt with one of the movable rails so constructed and so adjusted that when the switch occupies its normal position the head of said plunger bolt will engage said one end member and will hold said locking device to the position in which said plunger bolt is withdrawn from said notch in said lock rod. 25. The combination with a railway switch comprising two movable rails and two fixed rails and an operating device for said switch connected with the movable rails by means including a spring connecting rod, of a casing, a plate mounted in said casing for reciprocating between two extreme positions, rack teeth on the upper face of said plate, a shaft journalled in said casing and provided with a gear segment which meshes with said rack teeth, a foot pedal secured to said shaft, a lock rod secured to the movable rails of said switch for movement therewith and extending into said casing and provided within said casing with a notch, a locking device slidably mounted in said casing above said plate, said locking device comprising two spaced parallel side members connected by two parallel end members, one of which end members is provided with a hole, a locking plunger secured to the other end member and adapted to enter the notch in said lock rod when and only when the switch occupies its normal position, said locking device being movable when said locking plunger is within said notch to an extreme position which is beyond its normal locking position, two bolt members secured to said two end members and extending parallel to said two side members in spaced relation thereto, a pair of lugs on said motion plate each provided with a hole which slidably receives one of said bolt members, a hold down member secured to said casing above said lock rod and provided with two slots which receive said bolt members between said lugs and said other end member, two compressed coil springs one on each bolt member between said other end member and said hold down member for biasing said locking device to said extreme position, said lugs being so positioned on said plate and the parts being so proportioned that when said plate is moved from its one extreme position to its other extreme position said lugs will engage said one end member and will move said locking device to a position in which said plunger bolt is out of said notch in said lock rod, a plunger bolt extending through the hole in said one end member with some clearance and provided on its inner end with a head which is larger than said hole, and linkage connecting said plunger bolt with one of the movable rails so constructed and so adjusted that when the switch occupies its normal position the head of said plunger bolt will engage said one end member and will hold said locking device to the position in which said plunger bolt is withdrawn from said notch in said lock rod.

device in its normal locking position and that when a train trails the switch said bolt member will then engage said one end member and move said locking device to the position in which said locking plunger is withdrawn from said notch in said lock rod.

25. In combination, a spring switch, a lock rod connected with the movable rails of said switch and provided with a notch, a locking plunger adapted to enter said notch when and only when the switch occupies its normal extreme position to lock the movable rails in this position of the switch, said locking plunger being movable within said notch to an extreme position which is beyond its locking position, a spring for biasing said locking plunger to said extreme position, a treadle bar mounted adjacent one of the fixed rails of the switch for cooperation with the wheels of a train trailing the switch and movable between a raised and a depressed position, linkage connecting said locking plunger with said treadle bar in such manner that when said locking plunger is moved to its locking position by said spring said treadle bar will be moved to its raised position but that when said treadle bar is moved to its depressed position by the wheels of a car said locking plunger will be withdrawn from the notch in said lock rod, and indication means controlled by said locking plunger for indicating when said locking plunger occupies its locking position.

26. In combination, a spring switch, a lock rod connected with the movable rails of said switch and provided with a notch, a locking plunger adapted to enter said notch when and only when the switch occupies its normal extreme position to lock the movable rails in this position of the switch, a spring for biasing said locking plunger to said extreme position, a treadle bar mounted adjacent one of the fixed rails of the switch for cooperation with the wheels of a train trailing the switch and movable between a raised and a depressed position, linkage connecting said locking plunger with said treadle bar in such manner that when said locking plunger is moved to its locking position by said spring said treadle bar will be moved to its raised position but that when said treadle bar is moved to its depressed position by the wheels of a car said locking plunger will be withdrawn from the notch in said lock rod.

27. In combination with a railway switch comprising two movable rails and two fixed rails, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to the other will move said switch from its normal to its reverse position and vice-versa, a lock rod secured to the movable rails of said switch for movement therewith and extending into said casing and provided within said casing with a notch, a locking device slidably mounted in said casing above said motion plate, said locking device comprising two spaced parallel side members connected by two parallel end members, one of which end members is provided with a hole, a locking plunger secured to the other end member and adapted to enter the notch in said lock rod when and only

when the switch occupies its normal position, said locking device being movable when said locking plunger is within said notch to an extreme position which is beyond its normal locking position, two bolt members secured to said two end members and extending parallel to said two side members in spaced relation thereto, a pair of lugs on said motion plate each provided with a hole which slidably receives one of said bolt members, two springs one on each bolt member between said other end member and said lug for biasing said locking device to said extreme position, said lugs being so positioned on said motion plate and the parts being so proportioned that when said motion plate is moved from its one extreme position to its other extreme position to move said switch from its normal to its reverse position said lugs will engage said one member and will move said locking device to a position in which said locking plunger is out of said notch in said lock rod before the movable rails start to move, a plunger bolt extending through the hole in said one end member with some clearance and provided on its inner end with a head which is larger than said hole, a treadle bar mounted adjacent one of the fixed rails of the switch for cooperation with the wheels of a train trailing the switch and movable between a raised and a depressed position, linkage connecting said treadle bar with said plunger bolt in such manner that when said locking device is moved to its locking position by said springs said one end member will engage the head of said plunger bolt and will move said treadle bar to its raised position but that when said treadle bar is depressed the head of said plunger bolt will engage said end member and move said locking device to the position in which said locking plunger is withdrawn from said notch in said lock rod.

28. In combination, a railway switch comprising two fixed rails and two movable rails, a spring connecting rod comprising a tubular casing having one end closed by an end plate provided with an axially disposed hole and the other end closed by a cap provided with an axially disposed hole, a first rod extending into said casing through the hole in said end plate and provided at its inner end with a first cylindrical member which is adapted to slide within said casing, a second rod extending into said casing through the hole in said end cap and provided at its inner end with a second cylindrical member, a compressed coil spring surrounding said first rod between said end plate and said first cylindrical member, means for connecting said two rods with said two movable rails respectively, a lug on said casing, means connected with said lug for moving the switch between its normal and reverse positions, a lock rod connected with the movable rail which engages the associated fixed rail in the normal position of the switch and provided with a notch, a locking plunger adapted to enter the notch in said lock rod when and only when the switch occupies its normal position, means for biasing said locking plunger to the position in which it enters the notch in said lock rod, and linkage connected with said locking plunger and with the movable rail which is unlocked in the closed position of the switch, said linkage being so constructed and so adjusted that movement of said unlocked rail toward the associated fixed rail by the wheels of a train which is trailing the switch will cause said locking plunger to be

- withdrawn from engagement with the notch in said lock rod before a sufficient force is exerted on the locked rail to overcome the opposing force of the spring in said spring connecting 5 rod. 80
29. A spring connecting rod for connecting the movable rails of a railway switch comprising a tubular casing having one end closed by an end plate provided with an axially disposed hole and 10 the other end closed by an end cap provided with an axially disposed hole, a first rod adapted to be connected at one end with one of the movable rails of the switch and having its other end extending into said casing through the hole 15 in said end plate and provided within said casing with a first cylindrical member which is adapted to slide in said casing, a second rod adapted to be connected at one end with the other movable rail and extending into said casing through the hole in said end cap and provided at its inner end with a second cylindrical member which is adapted to slide in said casing, and a compressed coil spring surrounding said first rod between said end plate and said first 20 cylindrical member. 90
30. In combination, a railway switch, a signal for governing traffic over said switch comprising two electroresponsive devices each adapted when energized to display a different indication, 30 means for locking the movable rail of the switch which engages the associated fixed rail in the normal position of the switch in this position of the switch, a first contact controlled by said locking means, a point detector rod connected 35 with the same movable rail as said lock rod, a second contact controlled by said point detector rod, a relay provided with a circuit including said two contacts, a circuit for one of said electroresponsive devices controlled by a front contact of said relay, and a circuit for the other electroresponsive device controlled by a back contact of said relay. 100
31. In combination, a railway switch, a signal for governing traffic over said switch comprising 45 two electroresponsive devices each adapted when energized to display a different indication, means for locking the movable rail of the switch which engages the associated fixed rail in the normal position of the switch in this position of the 50 switch, a first contact controlled by said locking means, a point detector rod connected with the same movable rail as said lock rod, a second contact controlled by said point detector rod, a third contact controlled by traffic conditions 55 adjacent said switch, a relay provided with a circuit including said three contacts, a circuit for one of said electroresponsive devices controlled by a front contact of said relay, and a circuit for the other electroresponsive device controlled by a back contact of said relay. 110
32. In combination, a spring switch, a tie rod connecting the movable rails of the switch at a point approximately half way between the heel and the point of the switch, means for 60 rigidly locking the movable rails of the switch in one extreme position, and means connected with and actuated by said tie rod for unlocking the movable rails when a train trails the switch until after the train has completely passed the 70 switch. 115
33. In combination, a spring switch, a tie rod connecting the movable rails of the switch at a point approximately half way between the heel and the point of the switch, means for rigidly 75 locking the movable rails of the switch in one 120 extreme position, means connected with and actuated by said tie rod for unlocking the movable rails when a train trails the switch, and means effective after the train is completely past the switch for relocking the movable rails. 125
34. In combination, a spring switch, means for rigidly locking the movable rails of the switch in one extreme position of the switch, means connected with one of the movable rails at a point approximately half way between the heel and the point of the switch and responsive to the lateral forces which are set up in the associated rail when a train trails the switch for unlocking the movable rails, and means for relocking the rails as soon as the train is completely past the switch. 130
35. In combination, a switch comprising a pair of movable rails, means including a spring for operating the movable rails to their normal and reverse positions, means for locking the movable rails in their normal positions, means connected with one of the movable rails and responsive to the lateral movement of such one rail which takes place when a train trails the switch before a sufficient force is developed at the point 100 of the rails to overcome the opposing force of said spring for unlocking the movable rails, and means for relocking the movable rails in their normal positions after the train has completely passed the switch. 135
36. In combination, a spring switch, means for locking the movable rails of the switch in one extreme position of the switch, an operating bar associated with one of the rails adjacent the heel of the switch and adapted to be moved laterally away from such one rail by a train trailing the switch, and means operatively connected with said operating bar and responsive to movement of said operating bar away from such one rail for unlocking the movable rails. 140
37. In combination, a spring switch, means for locking the movable rails of the switch in one extreme position of the switch, an operating bar associated with one of the rails and adapted to be moved laterally away from such one rail by a train trailing the switch, and means operatively connected with said operating bar and responsive to movement of said operating bar away from such one rail for unlocking the movable rails. 145
38. In combination, a spring switch, means for locking the movable rails of the switch in one extreme position of the switch, an operating bar associated with one of the rails and adapted to be moved laterally away from such one rail by a train trailing the switch, means operatively connected with said operating bar and responsive to movement of said operating bar away from such one rail for unlocking the movable rails, and means effective after the train is completely past the switch for relocking the movable rails. 150
39. In combination, a spring switch, means for locking the movable rails of the switch in one extreme position of the switch, an operating bar associated with one of the rails adjacent the heel of the switch and adapted to be moved laterally away from such one rail by a train trailing the switch, means operatively connected with said operating bar and responsive to movement of said operating bar away from such one rail for unlocking the movable rails, and means effective after the train is completely past the switch for relocking the movable rails. 155
40. In combination, a spring switch, means

- for locking the movable rails of the switch in one extreme position of the switch, an operating bar biased toward one of the rails of the switch and adapted to be moved laterally away from such one rail by a train trailing the switch, and means operatively connected with said operating bar and responsive to movement of said operating bar away from such one rail for unlocking the movable rails. 80
- 10 41. In combination, a spring switch, means for locking the movable rails of the switch in one extreme position of the switch, an operating bar biased toward one of the rails of the switch and adapted to be moved laterally away from such one rail by a train trailing the switch, linkage connected with said operating bar, and means operated by said linkage for unlocking the movable rails. 85
- 15 42. In combination, a spring switch, a lock rod secured to one of the movable rails for movement therewith and provided with a notch, a locking plunger adapted to enter the notch in said lock rod when and only when the switch occupies its normal extreme position, means for biasing said locking plunger to the position in which it enters said notch, an operating bar biased toward one of the rails of the switch in such manner that it will be moved laterally away from said one rail by the wheel of a train trailing the switch, and linkage connected with said locking plunger and said operating bar in such manner that movement of said operating bar away from said one rail will move said locking plunger out of engagement with the notch in said lock rod. 90
- 20 43. In combination with a railway switch, spring means for moving the switch points to the normal or the reverse position, locking means biased to a locking position when and only when the switch points are in the normal position and effective when in the locking position for positively locking said switch points in the normal position, and automatic means effective when the switch points are in their normal position and a train approaches the switch in a trailing direction for withdrawing said locking means from its locking position and for subsequently holding said locking means in its withdrawn position until the train has completely passed the switch. 95
- 25 44. In combination with a spring switch, manually operable means for moving the switch to its normal or its reverse position, a lock rod connected with the movable rails of the switch and provided with a notch, a locking device biased to a locking position when and only when the switch is moved to its normal position by said manually operable means and cooperating when in its locking position with said notch to positively lock the switch in its normal position, and means for at times moving said locking device from its locking to its unlocking position. 100
- 30 45. In combination with a spring switch, manually operable means for moving the switch to its normal or its reverse position, a lock rod connected with the movable rails of the switch and provided with a notch, a locking device biased to a locking position when and only when the switch is moved to its normal position by said manually operable means and cooperating when in its locking position with said notch to positively lock the switch in its normal position, means controlled by said manually operable means for moving said locking device from its locking to its unlocking position prior to movement of the movable rails when the switch is being moved from its normal to its reverse position by said manually operable means, and means mechanically actuated by a train trailing the switch for moving said locking device from its locking to its unlocking position. 105
- 35 46. In combination with a spring switch, locking mechanism for said switch having a locking and an unlocking position and effective when in its locking position for locking the movable rails of the switch in one extreme position, means for at times biasing said locking mechanism to its locking position, and means connecting said locking mechanism with the movable rails of said switch and effective when said locking mechanism is biased to its locking position for transmitting to the movable rails a force which urges the movable rails to their proper positions in said one extreme position of the switch. 110
- 40 47. In combination with a spring switch, manual means for moving said switch between its two extreme positions, locking mechanism for said switch having a locking and an unlocking position and effective when in its locking position for locking the switch in one extreme position, means for biasing said locking mechanism to its locking position when the switch is moved to its one extreme position by said manual means, and means connecting said locking mechanism with the movable rails of the switch and effective when said locking mechanism is biased to its locking position for transmitting to the movable rails a force which urges the movable rails to their proper positions in said one extreme position of the switch. 115
- 45 48. In combination with a spring switch, manual means for moving said switch between its two extreme positions, locking mechanism for said switch having a locking and an unlocking position and effective when in its locking position for locking the switch in one extreme position, means for biasing said locking mechanism to its locking position when the switch is moved to its one extreme position by said manual means, and means connecting said locking mechanism with the movable rails of the switch and effective when said locking mechanism is biased to its locking position for transmitting to the movable rails a force which urges the movable rails to their proper positions in said one extreme position of the switch and for moving said locking mechanism from its locking to its unlocking position if a train trails the switch. 120
- 50 49. In combination with a spring switch, locking mechanism for said switch having a locking and an unlocking position and effective when in its locking position for locking the switch in one extreme position, linkage connected with the movable rails of said switch and with said locking mechanism and effective when the switch occupies said one extreme position and a train trails the switch for moving said locking mechanism from its locking to its unlocking position, and spring means for at times biasing said locking mechanism to its locking position and for simultaneously exerting a force on said linkage which urges the movable rails of said switch to their proper positions in said one extreme position of the switch. 125
- 55 50. In combination with a spring switch, manual means for moving said switch between its two extreme positions, locking mechanism for said switch having a locking and an unlocking position and effective when in its locking position for locking the switch in one extreme position, linkage connected with the movable rails of said switch and with said locking mechanism and effective when the switch occupies said one extreme position and a train trails the switch for moving said locking mechanism from its locking to its unlocking position, and spring means for at times biasing said locking mechanism to its locking position and for simultaneously exerting a force on said linkage which urges the movable rails of said switch to their proper positions in said one extreme position of the switch. 130
- 60 55. In combination with a spring switch, manually operable means for moving the switch to its normal or its reverse position, a lock rod connected with the movable rails of the switch and provided with a notch, a locking device biased to a locking position when and only when the switch is moved to its normal position by said manually operable means and cooperating when in its locking position with said notch to positively lock the switch in its normal position, and means for at times moving said locking device from its locking to its unlocking position. 135
- 65 56. In combination with a spring switch, manually operable means for moving the switch to its normal or its reverse position, a lock rod connected with the movable rails of the switch and provided with a notch, a locking device biased to a locking position when and only when the switch is moved to its normal position by said manually operable means and cooperating when in its locking position with said notch to positively lock the switch in its normal position, means controlled by said manually operable means for moving said locking device from its locking to its unlocking position prior to movement of the movable rails when the switch is

switch and with said locking mechanism and effective when the switch occupies said one extreme position and a train trails the switch for moving said locking mechanism from its locking 5 to its unlocking position, and spring means effective when the switch has been moved to said one extreme position by said manual means for biasing said locking mechanism to its locking position and for exerting on the movable 10 rails through the medium of said linkage a force which urges the movable rails to the position which they normally occupy when said switch occupies said one extreme position.

51. In combination with a spring switch, a 15 lock rod connected with the movable rails for movement therewith and provided with a notch, a locking plunger adapted to enter the notch in said lock rod when the switch occupies its normal position to lock the movable rails in 20 this position of the switch, said locking plunger being movable within said notch to an extreme position which is beyond a normal locking position, a tie rod connecting the movable rails at a point approximately midway between the heel 25 and the point of the switch, linkage operatively connecting said tie rod and said locking device in such manner that when said switch occupies its normal position said linkage will prevent said locking plunger from being moved past its normal locking position within said notch and that 30 when a train trails the switch the lateral bending of the movable rails which takes place before a sufficient force is developed at the points of these rails to cause the points to start to open

35

will move said locking plunger to a position in which it is withdrawn from the notch in said lock rod, and a spring biasing said locking plunger to its extreme position within the notch in said lock rod, whereby said spring acts not only as a means for moving said locking plunger to its normal locking position but also at times transmits through the linkage connecting said locking plunger and said tie rod a force which urges the movable rails to their normal positions at the point where the tie rod connects these rails.

52. In combination with a railway switch of the type which is adapted to be trailed, a switch stand including a manually operable lever operatively connected with the switch for moving the switch between its two extreme positions, lock mechanism effective after the switch has been moved to one extreme position by said lever for positively locking said switch in said one extreme position for facing point moves over the switch, means effective when said switch occupies said one extreme position and a train trails the switch for actuating said lock mechanism to unlock the switch until after the train 100 has completely trailed the switch, and means for connecting said lever with said lock mechanism in such manner that when said lever is operated to move the switch from said one extreme position to the other extreme position said 105 lock mechanism will be automatically operated to unlock the switch.
